SHOWERSTALL-BATHTUB

Samuel John Samelow, Chicago, Ill., assignor to
Bailey Samelow Stanton, Chicago, Ill.

Application September 22, 1933, Serial No. 690,545

11 Claims. (Cl. 4—146)

This invention relates to a certain new and useful bathroom appurtenance embodying, among other things, a jointless—or virtually jointless—showerstall-bathtub, cast or combined as a unit, corners rounded, in which the showerstall is reciprocally coextensive with its subtended bathtub.

One object of this novel combination is a smooth and level interior, without ridges, joints, folds and sharp angles, which in other ablution devices catch dirt, harbor germs and make cleaning difficult.

Another object of my unit is maximum showerstall space, accomplished by allowing for the chamber component horizontally substantially the same space as that occupied by the bathtub.

One novel characteristic of this device is simplicity of installation—as well as economy in construction. The unit is free from the complications involved in assembling diverse parts into a combination. It requires no special plumbing, designed to fit such piping as is provided in modern bathrooms.

Another unique feature of my unit is embodied openings to admit outside light and air into the bathroom.

The unit may be manufactured in enamel iron, Monel metal, or any other material suitable for bathtubs.

With the above and other objects in view other novel features have been incorporated into the present invention, and these are more fully described hereinafter, and graphically illustrated in the accompanying drawings which are made a part of this specification.

In the drawings:

Figure 1 is a front view of the Samelow showerstall-bathtub combination with the front broken to expose a part of the interior.

Figure 2 is a vertical cross section thereof taken along the line 2—2 of Figure 1.

Figure 3 is a horizontal cross section of the same taken along the line 3—3 of Figure 1.

Figure 4 shows one of its doors—the sliding type.

Figure 5 shows a horizontal cross section taken along 5—5 in Figure 4.

Figure 6 suggests a perspective view of my showerstall-bathtub combination.

Figure 7 is a vertical cross section taken along the line 7—7 in Figure 6.

Figure 8, a cross section taken at the line 8—8 in Figure 6, shows a U-shaped band, edging the top of Figure 6.

Figure 9 is a sectional view taken at 9—9 in Figure 11.

Figure 10 is an alternate vertical cross section taken along the line 7—7 in Figure 6.

Figure 11 is a cross section of Figure 6 taken along line 11—11 thereof.

Figure 12 is an alternate cross section of Figure 6 taken along line 11—11.

Figure 13 is a vertical view taken at 13—13 in Figure 12.

Figure 14 is a cross section view taken on line 14—14 in Figure 13.

Figure 15 is an alternate vertical cross section taken along line 2—2 in a figure similar to Figure 1.

Figure 16 is a cross section of Figure 15, taken along the line 16—16.

Referring to the drawings in detail wherein like characters of reference denote corresponding parts, the horizontal plane 39 in Figure 1 and Figure 2 is a rectangular floor substantially, merging at its four sides into four upright walls 37 and 38.

Externally, the four walls, cast jointly with the floor, constitute four plane surfaces. Internally the walls, at bathtub height, embody a ledge, as a result of a designed difference in wall thickness, whereby the upper part is recessed from the lower part of the shell.

The vessel thus molded directly below the ledge 30 with the ledge as its rim constitutes mechanically, in shape, functionally and in form a built-in bathtub.

The recessed part of the shell superimposed over the molded bathtub forms in combination with the subtended bathtub an ample showerstall, effecting for the bather the comfort and repose of a bathtub or the convenience of a showerbath, and for the bathroom superior curtain protection and an attractive appurtenance.

The enclosed bathtub, like its prototypes, is provided with the necessary openings for a drain 40 in Figure 1, overflow 41 in Figure 7 and supply pipes 42 in Figure 1.

The handle bars 35, U-shaped in form, extending from the walls with the U-corners into the interior of the unit, are incorporated as part of the casting. Placed at convenient points in the combination, these bars preclude slipping, which makes other appurtenances of this type sources of danger to life and limb. The recesses 34 molded back of the handle bars serve as soap holders.

An opening 30 is provided in the cast shell as shown in Figure 15 and Figure 16 which fits

around a building wall window 31 in a bathroom. This novel provision, together with the openings provided in the front wall of the unit like 26 and 27 in Figure 6, makes possible the transmission 5 of air and day light into the room even when the unit is placed against the window, which facility makes the Samelow unit adaptable even to small sized bathrooms, such as prevail in modern homes and apartments. The front wall openings, 10 in addition to their usefulness, enhance the attractiveness of the unit.

No. 28, like No. 18 indicates doors, situated directly over the bathtub rim, so arranged as to be out of the way of the bather. Various methods of hanging the doors are shown for which see Fig. 1, Fig. 2, Fig. 3, Fig. 4, Fig. 5, Fig. 6, Fig. 11, Fig. 12, Fig. 15 and Fig. 16.

The pivoted type door 18 swings around a pin extended from corners of the doors into corresponding sockets situated in the tub rim below and in the wall or bar which is extended over the top of the doorway.

The mechanical means of the sliding type of door for this unit become apparent by reference 25 to 21, a sash weight working over a pulley 28, the dotted line in Figure 4, marking the movement and position of the frame. Fig. 13, taken at 13-13 in Fig. 12, with its cross section view Fig. 14 taken along line 14-14, shows a hinge 30 for a door 18 in Figure 1.

The Samelow unit may be cast in two separate components as illustrated in Figures 6, 7 and 10. In Fig. 6, S indicates the chamber superimposed upon T, the bathtub, one engaging the other by 35 means of a tongue and groove joint 24, extending around the unit, or by a flange 24'. These joints not only interlock the two members of the unit but form a leak proof juncture. Dowels 25, Fig. 9, extending from the four corners of the 40 chamber into corresponding sockets 33 in the four corners of the bathtub are provided to assure the most secure position for the shower chamber.

The invention is susceptible to various changes. The details shown are for purposes of disclosure 45 and not as limitations. The right is herein reserved to make such changes as properly fall within the scope of the appended claims.

I claim:

1. A jointless substantially block-shaped showerstall-bathtub combination, comprising a base component formed like a standard bathtub, and a box-like component to serve as a chamber, the two components, reciprocally coextensive, cast or combined, corners rounded, as a unit with unitary exterior walls, set-off from each other on the interior by a continuous horizontal ledge which forms a rim for the thus built-in bathtub base.

2. A jointless substantially box-shaped showerstall-bathtub combination which comprises a base component formed like a standard bathtub, and a four-walled chamber component, the two components reciprocally coextensive, ledged off horizontally at their juncture on the inside to form a rim for the built-in bathtub base, the front wall of the chamber embodying a doorway opening for the combination.

3. A jointless substantially block-shaped showerstall-bathtub combination, corners rounded, which comprises a base component formed like a 70 standard bathtub, and a box-shaped chamber component ledged off horizontally at the juncture of the components on the inside to form a rim for the built-in bathtub base, the front wall of the chamber embodying an opening for a doorway and an opening on each side of the doorway

for panels or windows for the structure, which is cast or combined as a unit.

4. A substantially box-shaped showerstall-bathtub combination, cast, fused or moulded as a unit, all corners rounded, which comprises a base component formed like a standard bathtub, from whose walls extends upwardly a four walled chamber component, ledged off from the base at the jointure of the two components on the inside of the unit, the ledge forming a rim for the built-in bathtub component, the front wall of the chamber component embodying an opening for a doorway directly over the bathtub-rim and an opening on each side of the doorway for panels or windows, one of the other chamber walls embodying an opening to fit around a bathroom window.

5. A substantially box-shaped showerstall-bathtub combination, all corners rounded, which includes a base component formed like a standard bathtub, and a four walled chamber component, the two cast or combined as a unit but set off from each other on the inside of the unit by a continuous horizontal ledge forming a rim for the built-in bathtub component, the front and 25 back walls of the chamber each embodying an opening for a doorway and an opening on each side of each doorway for panels or windows.

6. In a combination showerstall-bathtub comprising two jointless sections in which the shower- 30 stall is coextensive with its subtended tub, a tongue-and-groove joint between the two sections, said joint comprising a continuous groove in the bathtub rim, and a continuous "tongue" edge in the bottom of the showerstall—whereby 35 the two jointless sections are combined into one box-shaped unit.

7. In a combination showerstall-bathtub comprising two jointless sections, the shower chamber as one section, and the bathtub base as the 40 other section, the two being coextensive, and a coveflange around the lower edge of the chamber, fitting snugly all around the bathtub rim, whereby a leak-proof union of the two jointless sections is effected.

8. In a combination showerstall-bathtub, comprising two jointless sections which are coextensive, the shower chamber as one section and the bathtub as the other section, and dowel pins extending from the corners of the showerstall which 50 fit into corresponding sockets in the corners of the bathtub.

9. A substantially block-shaped showerstall-bathtub combination, corners rounded, comprising a base component, formed like a standard 55 bathtub, and a box-shaped chamber component, the two components cast as a unit, with the walls of the chamber extending upwardly from the bathtub walls and ledged off horizontally at bathtub height on the inside of the combination to 60 form a rim for the built-in bathtub base, the chamber embodying substantially U-shaped handle bars which extend from the walls with the U-corners into the interior, and an opening in the front wall directly over the tub rim as a doorway for the unit.

10. A substantially jointless block shaped showerstall-bathtub combination, cast, fused or moulded as a unit, comprising a bathtub component superimposed by a cabinet component, the 70 two components being reciprocally coextensive, marked off from each other by a continuous ledge which forms a rim for the subtended bathtub, U-shaped handle bars extending from the walls with the U-corners into the interior of the unit,

the cabinet having openings in the walls for a doorway or windows.

11. A substantially box-shaped showerstall-bathtub unit comprising a bathtub component superimposed by a cabinet component, the two components being reciprocally coextensive, marked off from each other by a continuous ledge

which forms a rim for the subtended bathtub, U-shaped handle bars extending from the walls with the U-corners into the interior of the unit, the cabinet having openings in the walls for a doorway or windows.

5

SAMUEL JOHN SAMELOW.
